UNITED STATES PATENT OFFICE.

JACK D. KELLY, OF ELMHURST, NEW YORK.

WATERPROOF CARRYING CASE.

Application filed April 29, 1922. Serial No. 557,347.

To all whom it may concern:

Be it known that I, JACK D. KELLY, a citizen of the United States, and a resident of Elmhurst, borough of Queens, in the county of Queens and State of New York, have invented a new and Improved Waterproof Carrying Case, of which the following is a full, clear, and exact description.

This invention has relation to receptacles or containers and refers more particularly to a waterproof carrying case which is especially designed for bathers.

One of the principal objects of the present invention resides in the provision of a waterproof case which is adapted to contain cigarettes, matches, cosmetics, money, or the like, which is provided with means for attaching the same to a beach costume whereby the wearer may enter the water when the case is closed, with the assurance that the contents thereof will be protected from the water.

As a further object the invention contemplates in a carrying case of the character described means for effectively sealing the cover or closure element against the entrance of moisture, which means may be readily manipulated to facilitate the opening of the cover when desired.

As a further object the invention contemplates a device of the character described which is extremely simple in its construction and operation, inexpensive to manufacture and produce and which is thoroughly reliable and highly efficient in its purpose.

With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawing—

Figure 1 illustrates the use and application of a carrier case constructed in accordance with the invention.

Fig. 2 is an inner side view thereof illustrating the manner of attaching the same to a belt or other portion of the garment with which it is associated.

Fig. 3 is a vertical sectional view there-

through taken approximately on the line 3—3 of Fig. 2.

Fig. 4 is a plan view thereof with the cover partly broken away.

Referring to the drawing by characters of reference, the case comprises a tubular body 10 which is closed at its lower end and open at its upper end. A marginal exterior flange 11 is arranged adjacent to and spaced from the upper open end and the same is provided with a channel or groove 12 in the upper surface thereof within which the compressible gasket 13 is disposed. A tubular telescopic cover 14 is adapted to be associated with the upper open end of the body 10 and said cover is provided with a closed upper end and a lower open end, the edges of which are provided with an out-turned bead or flange 15 designed to be received within the groove or channel 12 of the flange 11. The closed end of the cover is provided with longitudinally sloping portions 16 which are inclined downwardly from a central elevated portion 17 having a transverse receiving notch or depression 18, the purpose of which will be hereinafter set forth. A substantially U-shaped bail 19 including side arms 20 and a connecting bight 21 at its upper end is pivotally associated with the body 10 for longitudinal swinging movement. The pivotal association of the bail with the body is accomplished by turning the free extremities of the side arms 20 inwardly to provide trunnions 22 which are received by the bearing sockets 23 provided on the opposite sides of the body 10. The bail 19 is of an appropriate length to forcibly impinge the flange or bead 15 on the lower open edge of the cover 14 against the gasket 13 when the bight 21 is arranged within the transverse depression 18. The parallel rounded beads 24 which define the depression 18 serve to prevent casual displacement of the bight 21 of the bail from the depression due to the inherent resilient action of the gasket which operates to force the cover against the bail. In removing or applying the cover, the bight 21 of the bail 19 is snapped over one of the beads 24 into or out of the depression 18.

100 In the drawing—
Figure 1 illustrates the use and application of a carrier case constructed in accordance with the invention.
Fig. 2 is an inner side view thereof illustrating the manner of attaching the same to a belt or other portion of the garment with which it is associated.
Fig. 3 is a vertical sectional view there-

tacle or case against the entrance of water or moisture. The body of the case is provided with suitable elements for attaching the same to the belt or other article with which the case is to be associated, said elements being specifically illustrated herein as safety pins 25, the pointed extremities 26 of which are engageable under the hooked terminals 27 and locked in place by the tubular slides 28. As specifically illustrated the flange 11 is formed on an external sleeve 29 which surrounds the mouth or upper open end of the body 10 and which is soldered, welded or otherwise secured thereto. Preferably the inner faces of the inclined portions 16 of the cover are serrated or roughened as at 30 to provide surfaces for igniting matches. The case may be employed for carrying cigarettes, matches, money, cosmetics, or any other articles which are desired to be carried on the person of a bather and which are to be protected from the water while permitting the case to be submerged therein.

25 I claim:

1. In a waterproof carrying case of the character described, a tubular body and cover each having a closed end and an open end and adapted for telescopic association, an exteriorly disposed channeled flange provided on the body adjacent the open end thereof, a resilient gasket therein, an out-turned flange or bead on the open end of the cover adapted to enter the channeled flange and engage the gasket, a bail pivoted

to the body for longitudinal swinging movement, a pair of centrally disposed upstanding parallel beads on the cover defining therebetween a receiving depression or groove for the reception of the bight of said bail, whereby upon engagement with the cover said bail will function to impinge the out-turned flange of the cover against the gasket and said gasket in turn will function to tensionally maintain the bight of the bail within the receiving depression against casual displacement.

2. In a waterproof carrying case of the character described, a tubular body and cover each having a closed end and an open end and adapted for telescopic association, an externally disposed flange provided on the body adjacent the open end thereof, a resilient gasket seated on said flange with which the open end of the cover is adapted to engage when in closed position on the body, a bail pivoted to the body for longitudinal swinging movement, a pair of centrally disposed upstanding parallel beads on the cover defining therebetween a receiving depression or groove for the reception of the bight of said bail, whereby upon engagement with the cover said bail will function to impinge the open end of the cover against the gasket and said gasket will in turn function to tensionally maintain the bight of the bail within the receiving depression against casual displacement.

JACK D. KELLY.
